[57] CLAIM

The ornamental design for a sun tan oil applicator, as shown and described.

DESCRIPTION

FIG. 1 is a front exploded view of the sun tan oil applicator of the present invention;

FIG. 2 is a rear view of FIG. 1;

FIG. 3 is a right side view of FIG. 1;

FIG. 4 is a left side view of FIG. 1;

FIG. 5 is a top view of FIG. 1;

FIG. 6 is a bottom view of FIG. 1; and,

FIG. 7 is a top front perspective view of the design in its assembled state.

The undisclosed inner surface of the top cap and underlying top of the threaded end form no part of the claimed design.

The undisclosed and obscured surfaces of the lower cap, applicator tip and overlying flang follow the contours of the sides shown.
